[57] CLAIM

The ornamental design for a top assembly for a planer, as shown and described.

DESCRIPTION

FIG. 1 is a left side perspective view from the front of a top assembly for a planer showing my new design;

FIG. 2 is a rear elevational view of my design;

FIG. 3 is a front elevational view of my design;

FIG. 4 is a left elevational view of my design;

FIG. 5 is a right elevational view of my design; and,

FIG. 6 is a top plan view of my design.

In the attached drawings, any broken line illustration is not part of the design sought to be patented.
